B. D. JONES.
CAR DOOR STRUCTURE.
APPLICATION FILED MAR. 3, 1911.

1,036,634.

Patented Aug. 27, 1912.

UNITED STATES PATENT OFFICE.

BELDEN D. JONES, OF CHICAGO, ILLINOIS, ASSIGNOR TO JONES CAR DOOR COMPANY, OF CHICAGO, ILLINOIS, A CORPORATION OF MAINE.

CAR-DOOR STRUCTURE.

1,036,634.

Specification of Letters Patent. Patented Aug. 27, 1912.

Application filed March 3, 1911. Serial No. 612,040.

To all whom it may concern:

Be it known that I, BELDEN D. JONES, a citizen of the United States, residing in the city of Chicago, county of Cook, and State 5 of Illinois, have invented certain new and useful Improvements in Car-Door Structures, of which the following is a specification.

This invention relates to improvements in 10 car door structures and refers more particularly to that type of car doors used on railway freight cars.

Among the salient objects of the invention are to provide a construction which can 15 be readily opened and closed without binding and which effectively forms a close weather-proof fit with the car body so as to prevent any moisture or water from entering the car and which avoids any unpro- 20 tected joints between the car door opening and car door; to provide in a construction of the above character improved means for securing a weather-tight joint at the 25 ends of the door when the latter is in closed position; to provide a construction which 30 is simple and economical in manufacture and is nevertheless reliable in operation; and in general to provide an improved construction of the character referred to.

The invention consists in the matters hereinafter described and more particularly pointed out in the appended claims.

In the drawings the figure is a fragmentary horizontal sectional view of a car door 35 equipped with my invention.

In devices of this general character difficulty has heretofore been experienced in obtaining a weather-proof door structure which at the same time can be readily 40 opened and closed. Numerous devices have been patented aiming at the above objects but all of them have been more or less failures either because they were not in fact weather-proof fits after the door had been 45 subjected for some time to weather conditions in actual practice, or because they were so complicated or impracticable that they would not open and close readily after the door had been in use for any appreciable 50 length of time. The present invention while more or less simple in its details of construction has nevertheless obtained the aforementioned objects in actual practice.

Referring to the drawings—10 designates 55 as a whole a freight car provided with a

sliding door 11, mounted to slide across the car door opening. The side edges of the door are provided with angle irons 12 and 13 respectively, which extend throughout the height of the door. When the door is 60 closed it abuts against the door stop 22, at one end, in the usual manner. As I have heretofore stated difficulty has been experienced in preventing moisture or rain from leaking or seeping by the vertical edges of 65 the door into the car body. To this end one door post 23 is provided with a vertically extending rabbet or channel 24 so formed that its outer side 25 is in alinement with the angle plate 12. As shown in 70 the drawing the sides of the channel are practically formed by a door stop 22 and a portion of the door post 23 which projects beyond the plane of the car body. The arrangement is such as to prevent any moisture from leaking or seeping by the door post into the car body. The other door post is so arranged that the rear end of the door, when the latter is in closed position, extends 75 slightly beyond the projecting end 27 of the door post 26, forming in effect a vertical channel 28. Within this channel 28 is secured a vertically extending weather guard 29 which is secured by screws 30 to the post 26. In order that this guard may be more 80 fixedly held in position it is secured to the post before the sheathing 31 is applied to the car body. The outer end of this weather guard 29 terminates in a hook-shaped extension 32 which abuts against the over-lapping flange 13' of the angle iron 13 when the door is in closed position. In order to more effectively prevent lateral displacement of the door when it is in closed 85 position, I provide the same with an edge plate 33 having at its inner end an in-turned lip 34, which over-laps the flange 13' and the channeled extension 32. This edge plate 33 extends from the lower edge of 90 the door upwardly a short distance.

From the foregoing it will be seen that I effectively prevent any water or moisture from leaking into the car body when the door is in closed position. What water gets by the angle plate 12 will pass into the channel 24, while any water which attempts to enter the car at the other end of the door will be caught in the channel 28.

The object and operation of the various 105 parts heretofore described is apparent and 110

needs no further description. The invention, however, is not limited to the details of construction shown except as set forth in the appended claims.

5 I claim as my invention:

1. The combination with a car body having a car door opening, of a door mounted to slide across said opening, a door post at either end of said opening, a door stop at one end thereof, the post adjacent said stop projecting beyond the plane of the car side and forming with the adjacent edge of the stop a vertically extending channel of substantial depth in cross section, the outer side of said channel formed by the face of the stop, being substantially flush with the adjacent edge of the door, when the latter is in closed position, whereby moisture or water leaking past the vertical edge of the door when the latter is in closed position, will pass into the channel and down through

the open end of the latter instead of entering the car.

2. The combination with a car body having a car door opening, of a door mounted to slide across said opening, a door post at either end of said opening, a door stop at one end thereof, the post adjacent said stop being rabbeted to form a vertically extending channel of substantial depth in cross section, the outer side of said channel being substantially flush with the adjacent edge of the stop when the latter is in closed position, whereby water or moisture leaking past the vertical edge of the door, when the latter is in closed position, will pass into the channel and down through the open end of the latter instead of entering the car.

BELDEN D. JONES.
